UNITED STATES PATENT OFFICE.

CLARENCE E. SALLADA, OF MINNEAPOLIS, MINNESOTA.

AIR MOISTENER.

Application filed December 14, 1927. Serial No. 240,039.

This invention relates to means for imparting moisture to the hot air circulating from a hot-air furnace for heating buildings. It is well known that the heated currents sent through a building from a hot-air furnace are very dry and tend to cause shrinkage of woodwork with consequent loosening of the joints in furniture and the wooden trim of buildings and many attempts have been made to impart moisture to these heated currents so as to overcome the stated shrinking and joint loosening. The object of the present invention is to provide a simple mechanism which may be readily installed in any hot-air furnace and in which all floats and similar actuating elements will be eliminated so that the operation of the device will be certain at all times, and a further object of the invention is to provide a mechanism which will be simple in construction without any loss of efficiency. These stated objects, and other objects which will incidentally appear in the course of the following description, are attained in such an apparatus as is illustrated in the accompanying drawings, and the invention resides in certain novel features which will be particularly pointed out in the appended claims.

In the drawings:

Figure 1 is an elevation, partly broken away, of the upper portion of a hot-air furnace having my improved air moistener installed therein;

Fig. 2 is an enlarged longitudinal section through the air moistener;

Fig. 3 is a transverse section on the line 3—3 of Fig. 2;

Fig. 4 is a front end elevation of the receiving cup attached to the evaporating pan or trough, and

Fig. 5 is an enlarged detail elevation of a portion of the cut-off valve and its mounting.

Fig. 6 is an enlarged section of the cut-off valve.

In the drawings, the reference numeral 1 indicates the outer casing or shell of a hot-air furnace having the usual openings 2 through its crown to receive the ends of the hot-air circulating flues, while the reference numeral 3 indicates a portion of the fire-box of the furnace.

In carrying out the present invention, there is provided an evaporating pan or trough 4 which is preferably constructed of sheet metal and is mounted in the crown of the fur-

nace immediately over the top of the firebox, as shown in Fig. 1. To support the pan, there is provided a telescopic beam consisting of a tube 5 and a rod 6 slidably fitted in the tube, the telescopic construction of this supporting beam permitting it to be adjusted to the diameter of the furnace crown so that the device may be set in a furnace of any size. The front end of the tube 5 is externally threaded so that it may be engaged in an internally threaded socket or boss 7 upon a head 8 which head is a casting having a vertically extending slot 9 through its lower portion for a purpose which will presently appear. Secured by screws 10 or other fasteners to the rim of the head 8 is the outer end of a cylindrical casing 11 which extends through an opening cut therefor in the side of the furnace shell, and to the top of this casing is secured an angle bracket 12 which is also secured to the furnace shell, as will be understood upon reference to Fig. 2. The outer or rear end of the rod 6 extends through a narrow slot 13 formed in the shell of the furnace diametrically opposite the opening which receives the casing 11, and upon the outer side of the shell is secured a guiding and holding plate 14 which has its central portion longitudinally offset and formed with a slot 15 which receives the end of the rod 6. The end of the rod 6 is engaged in an opening provided therefor in a metallic strap 16 which is disposed within the offset portion of the holding and guiding plate 14 and between the same and the side of the furnace so that, if this strap be moved longitudinally, the end of the rod 6 will be correspondingly adjusted and the supporting beam thus readily brought into a level position. After the supporting beam has been properly set, the upper end of the strap 16 is bent over the upper end of the plate 14, as shown at 17 in Fig. 2, so that the parts will be set in the position to which they have been adjusted.

On the outer side of the head 8 and preferably aligned with the boss 7 is an outer boss 18 having an opening 19 therein to receive a stud 20 whereby to support the inflow-controlling device, the stud being secured in the opening by a set screw 21 in an obvious manner. The stud 20 is formed on a block 22 which has a top threaded portion whereby it may be engaged in the lower end of a crown 23 having a nipple 24 on its upper side to receive the end of a water feed pipe 25, the end of said pipe being secured in the nipple

by a cap 26 of the usual slip-joint construction. This pipe 25 is preferably a small copper tube which may be easily set into the pipe which brings the water supply into the building and it delivers the water through an opening 27 in the top of the crown 23, as will be understood. The block 22 has a passage 28 extending from its upper surface to communicate with a radial passage 29 shaped to form a seat for a needle valve 30 threaded in the block and projecting from the front of the same, a packing box or gland 31 being mounted around the stem of said valve, as shown in Fig. 2, to prevent leakage. From the cross passage 29, an outlet passage 32 extends downwardly through the block or casting 22. Resting upon said block 22 within the crown 23 is a screen 33, and above said screen filtering material 34 is placed within the crown to fill the same.

The evaporating pan or trough 4 is provided in its front end near its bottom with a port 35 through which the water may pass into the pan and secured to the front end of the pan is a receiving cup 36 which is cast and is formed with an opening 37 in its top to admit the water. As shown in Figs. 4 and 5, this receiving cup is somewhat narrow and, as shown in Fig. 2, its bottom is preferably flush with the lower side of the port 35 so that the water delivered into the cup will be directed at once into the evaporating pan. The cup is provided with lateral flanges 38 through which screws, rivets or other fasteners are inserted to secure the same to the front end of the pan and from the top of the cup fastening arms 39 diverge to be secured to the front end of the pan and reinforce the same so that any tendency of the end of the pan to buckle will be resisted. The cup is provided with a drain opening in its bottom normally closed by a plug 40 and in its front end immediately adjacent its top is formed with an overflow nipple 41 whereby any excess of water which may accumulate under an emergency will be permitted to discharge, and it will be noted that this overflow is in a vertical plane beyond the side of the furnace so that any water which may possibly escape through the overflow nipple or spout will drop upon the cellar floor outside the furnace and will not run down upon the furnace shell to cause rusting of the same. Pivotaly attached to the sides of the cup adjacent the top thereof and spanning the inlet opening 37 is a yoke 42 which carries a cup 43. As shown most clearly in Fig. 2, this cup 43 is a cylindrical member, preferably of sheet copper, having an open upper end and having a bottom portion resting upon the yoke 42 and provided centrally with an opening through which passes a nipple 44, said nipple also passing through an aligned opening in the top of the yoke and being externally threaded to receive a securing nut 45. The nipple 44 is

formed as an integral part of a T-fitting having its head 46 extending diametrically within the cup 43 and adapted to rest upon the bottom of the cup, a gasket 47 being interposed between the head 46 and the bottom of the cup to prevent leakage in an obvious manner. When the nut 45 is turned home against the yoke 42, obviously the cup 43 will be clamped upon the yoke. The head portion of the T-fitting is provided on its upper side with an annular rim 48 within which is seated a washer or gasket 49, and this washer, which may be of any approved form or material, is removably held in its seat by a cap 50 having a depending resilient rim 51 formed with a bead 52 adapted to engage in an annular groove 53 formed in the outer surface of the rim 48, as clearly shown in Fig. 6. It should be understood, however, that a needle valve may be substituted for the washer, if desired. Below the bead 52, the rim of the cap is spread, as shown at 54, whereby it may easily ride over the rim 48 and spring into engagement therewith, the flared formation also facilitating spreading of the cap when it is necessary to remove the same to permit renewal of the washer. The cap 50 is, of course, provided with a central opening 55 to permit the washer 49 to seat against the lower end of the nipple 32 and thereby cut off the flow in the operation of the apparatus. As shown in Fig. 2, the nipple 32 is provided with an external annular rib 56 which fits within the upper portion of the cup 43 and thereby serves to guide said cup and maintain it in a vertical position when it moves with the evaporating pan and the receiving cup as the mechanism operates in the manner hereinafter set forth.

As before stated, the evaporating pan is formed of sheet metal and desired rigidity may be imparted to the top of the same by forming re-entrant flanges 57 along the edges of its sides, as shown most clearly in Fig. 3. Fitted upon the supporting beam immediately adjacent the inner end of the casing 11 is a bracket including a central eye or body portion 58 having a set screw 59 mounted therein whereby it may be secured upon the tube 5, and a yoke 60 which spans the top of the evaporating pan and has its terminal portions disposed at the outer opposite sides of the same to receive a fulcrum pin or rod 61 which passes through said terminals and the sides of the pan and may be secured by cotter pins 62 or other preferred means. Spaced inwardly from the eye 58, a second eye or bracket 63 encircles the tube 5 and is secured thereto by a set screw 64. The eye 63 is provided on its under side with lugs or ears 65 which depend within the top of the evaporating pan and receive a cross pin 66, as shown. Mounted upon the pin 66 between the lugs 65 is an angle bracket or fitting 67 having one tubular arm or branch presented to the rear

end of the pan and another tubular arm or branch presented downwardly and forwardly. A supporting pin or stud 68 is secured in the rearwardly presented branch 5 and extends through an opening provided therefor in the rear end of the pan while a counter-balance rod 69 is secured in the downwardly and forwardly presented arm and is equipped at its free end with a counter-weight 10 70, as clearly shown in Fig. 2.

It is thought the operation will be readily understood from the foregoing description, taken in connection with the accompanying drawings. The normal working position of 15 the parts is shown in Fig. 2, the cut-off valve, consisting of the washer 49 and the parts associated therewith, being opened or spaced away from its seat which is defined by the end of the outlet nipple 32 so that water may flow 20 into the receiving cup and thence pass into the evaporating pan. In installing the apparatus, the needle valve 30 is set so that the water will flow at the rate which judgment and experience may show to be best adapted 25 for successful use in a furnace of the size in which the device is being installed. The water will tend to accumulate in the evaporating pan and normally the weight of the receiving cup and the front end of the pan together with the weight of the water therein 30 and the leverage exerted by the counter-balance arm 69 and the counter-weight 70 will hold the pan in the position shown in Fig. 2. Should the water continue to accumulate in 35 the pan, it will reach the back of the pan and eventually it will overcome the leverage exerted by the counter-balance and the rear end of the pan will move downwardly, the pan rocking about the fulcrum rod 61 in an obvious manner and this movement will carry 40 the receiving cup and the cut-off valve upwardly so that the washer 49 will seat against the lower end of the nipple 32 and cut off the further flow of water, it being noted, particularly upon reference to Fig. 1, that the fulcrum 61 of the pan is nearer the front end of the same than the back end thereof so that the back end of the pan tends to overbalance 45 its front end. As the water evaporates, eventually, the leverage exerted by the counter-weight will prevail and the counter-weight will move downwardly so that the pin or stud 68 will swing upwardly and lift the rear end of the evaporating pan thereby 50 restoring the parts to the position shown in Fig. 2. The rate at which the water is flowing may be observed through the open space within the yoke 42 below the outlet nipple 44 of the cut-off valve and the needle valve 30 55 should be set so that the water will merely drip from said nipple. Ordinarily, the ratio between the feeding of the water and the evaporation of the same will be constant and a constant supply of vapor will be fed to the hot 60 air currents passing out through the building. 65

Should the fire fail without the fact being noticed, the weight of the accumulated water will serve to cut off the further flow in the manner previously described so that flooding will be avoided but, if, for any reason, 70 there should be an excessive accumulation of water, the overflow nozzle 41 will permit the same to escape without causing any serious damage. The water passing into the evaporating pan will be filtered and cleaned 75 in its passage through the filtering material 34 and the screen 33 so that ordinarily it will be free of foreign matter and there will be no sediment in the evaporating pan or the receiving cup. Should there be any sediment, 80 however, and it should be necessary to clean out the pan or the cup, this may be easily accomplished by removing the drain plug 40 and flushing the pan and the cup. The water will pass through the several passages in the 85 block 22 in an obvious manner and, striking upon the washer 49, will be spread to escape over the top and sides of the same and will find an outlet through the diametric passage in the head or body 46 of the T-fitting and 90 then escape through the depending nipple 44 thereof. If it should be necessary to repair or renew any of the parts of the cut-off valve, the flow of water from the main supply pipe is checked by closing the usual cut-off valve 95 provided therein, and the cut-off valve with the cup 43 may be removed by withdrawing the pivot screws which attach the yoke 42 to the receiving cup 36, the regulating valve and filter remaining in place upon the head 100 8. If it be desired to inspect or renew or repair the filtering material or the regulating valve 30, removal of the set screw 21 will permit the block 22 with the parts mounted thereon to be removed without necessitating 105 removal of other parts. The apparatus is very simple in construction, compact in arrangement and certain in operation.

It will be noted that in my present apparatus there are no floats employed. These 110 floats have been heretofore used and were connected with the cut-off valve so as to be actuated by the level of the water in the evaporating pan but they were uncertain in operation because they were apt to get out 115 of order and any slight deposit upon the fulcrum of the float or any of the elements connected therewith would interfere with the successful action. In my present apparatus, the space which is occupied by the float in the 120 arrangements heretofore generally employed is available for the storage of the water and the weight of the water itself operates to rock the evaporating pan so that the pan serves as a lever to raise and lower the cut-off valve 125 and thereby automatically control the inflow of the water to be evaporated.

Having thus described the invention, I claim:

1. In an air-moistening apparatus, the 130

- combination of supporting means, an evaporating pan mounted on the supporting means for rocking movement, means for supplying water to the evaporating pan, and 5 a cut-off valve carried by one end of the pan whereby upward movement of said end of the pan will cut off the flow of water and downward movement thereof will permit the water to flow.
- 10 2. In an air-moistening apparatus, the combination of supporting means, an evaporating pan mounted on the supporting means for rocking movement, means for supplying water to the pan through the 15 front end thereof, a cut-off valve carried by the front end of the pan, and a counter-weighted arm mounted adjacent the rear end of the pan and engaged with the rear end of the pan the weighted end of the arm extending forwardly within the pan.
- 15 3. In an air-moistening apparatus, the combination of a supporting beam, means whereby said beam may be secured in the shell of a furnace, a bracket secured on said beam, an evaporating pan pivotally carried by said bracket, a water-supplying element mounted adjacent the front end of the pan, a cut-off valve carried by the front end of the pan and movable therewith to permit or 20 stop flow from said element, and a counter-balance within the pan rockingly supported on the beam and engaged with the rear end of the pan.
- 25 4. In an air-moistening apparatus, the combination of a supporting beam, means whereby said beam may be secured within the top of a furnace shell, an evaporating pan pivotally carried by said beam, a water-supplying element mounted adjacent the 30 front end of the pan, a cut-off valve carried by the front end of the pan to be moved thereby toward and from said supply element, a bracket secured on the supporting beam adjacent the rear end of the pan, an angle member pivoted in the lower portion of said bracket, a pin extending rearwardly from said angle member and engaged through the rear end of the pan, and a counter-weight engaged in said angle member and extending downwardly and forwardly therefrom.
- 35 5. In an air-moistening apparatus, the combination of a tubular casing, means for securing said casing in one side of a fur-
- nace shell, a head secured in the outer end 55 of said casing, a supporting beam secured at one end to said head and at its opposite end in the shell of the furnace, an evaporating pan pivotally supported on said beam and having its front end disposed within 60 the casing, a receiving cup secured upon the front end of the pan and extending through said head, a mechanism secured to the head above the receiving cup for permitting and regulating inflow of water, and a cut-off 65 valve carried by the receiving cup and co-operating with said mechanism.
6. In an air-moistening apparatus, the combination of a supporting means including a head having an opening through its lower portion, an evaporating pan mounted for rocking movement upon said supporting means, a receiving cup secured upon the front end of the pan and extending through the opening in said head, said receiving cup 70 having an inlet opening through its top and the front end of the pan having a port therethrough at the bottom of the receiving cup, a water supplying and regulating device mounted upon the head above the cup and so having a depending outlet nipple, a yoke pivotally mounted upon the receiving cup adjacent the top of the same, a retaining cup carried by said yoke, and a T-fitting having a head within said retaining cup carrying a washer adapted to seat against the lower end of said outlet nipple and having a depending 75 nipple to direct water through the inlet opening of the receiving cup.
7. In an air-moistening apparatus, the combination of supporting means including a head having an opening through its lower portion and having an external boss above said opening, an evaporating pan mounted for rocking movement upon the supporting 80 means, a receiving cup secured upon the front end of the pan and extending through the opening in the head, a block secured in the boss on the head and having water passages therethrough, a regulating valve mounted in one of said passages, a cut-off valve carried by the receiving cup and movable therewith toward and from the outlet end of said passages, and a filtering chamber 85 on the upper side of said block.
- 105 In testimony whereof I affix my signature.

CLARENCE E. SALLADA. [L.S.]
